CLAIM

The ornamental design for an eyelash extension package, as shown and described.

DESCRIPTION

FIG. 1 is an isometric view of an eyelash extension package, in a closed configuration, showing our new design;

FIG. 2 is a top view thereof;

FIG. 3 is a bottom view thereof;

FIG. 4 is a side elevation view, the opposite side showing a mirror image thereof;

FIG. 5 is an isometric side view, the opposite side showing a mirror image thereof;

FIG. 6 is a front side view thereof;

FIG. 7 is a rear side view thereof;

FIG. 8 is a top view in an open configuration; and,

FIG. 9 is an isometric side view in an open configuration. A fourth side that is on an opposite side from the first side is a mirror image of the first side shown in FIG. 4 and FIG. 5.

The broken lines showing the text and ribbon are for the purpose of illustrating portions of the article and form no part of the claimed design.
